LIFEBOAT AND LAUNCHING TACKLE
THEREFORIvan Rupert Fleming and Frank Elder Fleming,
Liverpool, EnglandApplication February 10, 1939, Serial No. 255,760
In Great Britain February 18, 1938

11 Claims. (Cl. 9—23)

This invention relates to an improved lifeboat and launching tackle therefor.

According to present practice a ship's boat is generally lowered by boat lowering gear of the kind comprising one or more falls of ropes by which the boat is suspended and lowered and which are looped through a fall block detachably connected, as by a hook, to a fitting in the boat so that when the boat is water borne the fall block suspended on the lower end of the fall 10 is cast off.

The object of the invention is to provide a boat in which the fall block forms a permanent fitting in the boat and is constructed so that the fall or falls can be cast off the block instead of casting the block together with the falls off the boat as in the known practice described. This arrangement gives a very material advantage in that the aforesaid fall blocks are heavy and when the boat is cast off the heavy fall 20 block is suspended at about the head level of the passengers in the boat and, due to relative motion between the boat and the fall block, the block may strike the passengers and serious injury may result. By the arrangement according to the invention in which the falls are cast off the block and the block remains in the boat the above source of danger is eliminated.

Another object of the invention is to provide a fall block which forms a permanent part of 30 the fittings of the boat and which is so constructed that it can replace the present day lowering hooks mounted in the boat and on to which the present day fall blocks suspended from the falls are hooked. Thus the independent function of the hook and the fall block are combined in one fitting.

The invention will be further described by way of example with reference to the accompanying drawings, whereon—

Figure 1 is a side elevation of a ship's lifeboat fitted with a fall block according to the present invention.

Figure 2 is a plan view of Figure 1.

Figure 3 is an end elevation of the boat shown in Figures 1 and 2 in the stowed position in which it is nested in the cradle of the ship's davits.

Figure 4 is an end elevation in detail of the fall block and mounting therefor.

Figure 5 is a side elevation of Figure 4.

Figure 6 is an end elevation similar to Figure 4 but with the fall block tilted to permit the fall rope to be cast off.

Figure 7 is an end elevation of a modified form

of fall-block constructed according to the invention, and

Figure 8 is a side elevation of the block shown in Figure 7.

The gear 10 at opposite ends of the boat for suspending the boat from the fall ropes during launching is of similar construction and therefore it will only be necessary to describe the gear at one end of the boat, in detail.

The fall block and its mounting 10 comprises a standard 12 by which the block is permanently secured in the boat, the lower part of the standard being riveted to the keelson 13 as indicated at 14 in Figure 1. The standard 12 is reduced at 15 to provide a bearing 16 for a swivel block 17 which is rotatably mounted on the reduced part 15 of the standard and is held in position on the standard by a collar 18. The swivel block is provided with laterally extending trunnions 19 which support cross-head members 20 free to rock to a limited extent on said trunnions, the cross-head members being located on either side of the swivel block 17. A bracket 21 is fixed between the cross head members 20 at one side thereof, and is rigidly secured to said cross head members by screws 22 as indicated in Figure 1. A hook 23 is located between the cross head members at the opposite side thereof and is fixed on a shaft 24 journalled in said members. The fall block comprises a sheave 25 located between cheek plates 27 and mounted on a spindle 26 supported in bearings 28 and 29 on either side of the cheek plates. The cheek plates have strengthening ribs 27a. The bearing 28 is pivotally supported on the bracket 21 by means of a pivot pin 30 whilst the bearing 29 carries a pin 31 adapted to be engaged by the hook 23. The cheek plates 27 are secured to the bearings by screws 32 as indicated in Figure 5, and the spindle 26 is retained in position in the bearings 28 and 29 by nuts 33 on the ends of the spindle. The hook 23 is in two parts 23a and 23b (see Figure 5) and each part is adapted to engage one end of the pin 31. 40 Side plates 34 are mounted on the sides of the hook to prevent the nose portion 35 thereof engaging the fall rope 36 when said rope is cast off the sheave 25. An eye 37 is secured to the fall block by means of lugs 38 which are connected to the bearing blocks 28 and 29 by pins 39 and 40 respectively.

To disengage the pin 31 and the hook 23 so that the fall block can be opened into the position shown in Figure 6 to permit the fall rope 55 36 to be cast off the sheave 25, a releasing gear

is provided which comprises arms 41 fixed on the spindle 24 carrying the hook 23. The arms 41 are connected by pins 42 to links 43 which are coupled by pins 44 to a member 45 slideable vertically on the standard 12. The member 45 has claws 46 which engage an actuating member 47 which is also slideable vertically on the standard 12. The actuating member 47 is connected by links 48 to a bell crank lever 49 journaled in the boat. The bell crank levers 49 of the launching gear at opposite ends of the boat are connected by cables 50 and 51 to a common operating handle 52 the cables being led through tubing 53 mounted on a longitudinal bulkhead 54 of the boat.

Normally, that is when the boat is stowed in the davit cradle on board ship, a horn 55 on the davit cradle projects through the eye 37 so as to relieve the fall rope of the weight of the boat. When it is desired to launch the boat, the boat is slung out-board by the davits in the usual manner and is lowered by the fall ropes until it is water borne. Immediately the boat is water borne, the handle 52 can be pulled so that the bell crank levers 49 of the two sets of gear at opposite ends of the boat raise the actuating members 47 and the members 45 and thereby through the links 43 move the hook 23 from engagement with the pin 31 so that the hook moves into the position shown in Figure 6 and the fall block is tilted about the pivot pin 30 so that the fall ropes are cast off the sheaves 25. Generally the falls will slip automatically off the sheaves and it will be appreciated that the fall block can tilt to a greater extent than that shown in Figure 6 by rocking the cross-head members 20 about the trunnions 19. This movement of the cross-head members about the trunnions also enables the fall block to cant to whatever line the falls may take up as the boat is being lowered. Furthermore the swivel connection of the fall block to the standard 12 by means of the swivel block 17 enables any twists in the fall ropes to be readily unravelled. It is desirable to be able to unravel any twists in the fall ropes when a water-borne boat has to be raised to its stowed position on deck. For this operation the loops of the fall ropes are re-engaged in the sheaves of the blocks and the latter closed. A preliminary tensioning is applied to the fall ropes and they are unravelling by rotation of the fall block about a vertical axis so that the fall ropes run freely through the blocks.

It will be appreciated that the connection of the bell crank 49 and the links 48 to the member 45 by means of the claws 46 permits the member 45 and thereby the cross-head members 20 to swivel freely about the standard 12. Furthermore, in the engaged position of the hook 23 the pin 42 is substantially coaxial with the trunnions 19 so that the cross-head members 20 can rock on said trunnions without any tendency to disengage the hook 23.

A stop 55 is provided on the bracket 21 to limit the tilting movement of the fall block and abutments 56 may be provided on the standard 12 to limit the canting movement of the cross-head members about the trunnions 19. A detent 57 is pivotally connected to one of the cross-head members 20 on a pin 58 and when the detent is swung into the position shown in Figure 5 it engages the rear face of the hook 23 to prevent release thereof. Extension pieces 59 are provided on the lower part of the left hand cheek 27 of the fall block as shown in Figure 4. These ex-

70 tension pieces prevent the fall rope becoming entangled with the underface 60 of the cheek plate.

In the modification shown in Figures 7 and 8 each fall block for attaching the fall ropes to the forward and after ends of the boat comprises a standard 61 adapted to be secured to the bottom of the boat, for example, in a similar manner to the standard 12 described with reference to Figures 1 and 2. Cheek plates 62 and 63 are bolted to the upper part of the standard by bolts 64 and the cheek plate 63 is provided with a hinged part 65 which is hinged to the part 63 as indicated at 66. The hinged part 65 is provided with a stub 15 axle 67 on which is journaled a sheave 68. A lug 69 is secured to the hinged part 65 and normally projects through an aperture 70 in the side plates 62 and a pin 71 is inserted in a hole in the lug 69 so as to prevent the disengagement 20 thereof from the side plate 62 whereby the sheave 67 is maintained in alignment with the fall rope 36. When the boat being launched is water-borne the pins 71 of the launching gear at opposite ends of the boat are removed so that the hinged parts 65 pivot about their hinges to open 25 the blocks and tilt the sheaves 68 whereby the fall ropes are cast off said sheaves. It will be appreciated that with this construction the cheek plates 63 and 64 may be connected to the standard 61 so that they can be swivelled thereon about a vertical axis and can also cant about a horizontal axis in a similar manner to the fall block described with reference to Figures 3 to 6.

We claim:

35 1. In combination a boat, a standard permanently secured to the boat and having a swivel block on the upper part thereof, cross-head members, pivotal mountings at opposite sides of the swivel block for the said cross-head members, a fall block having a rotatable sheave, a hinged connection between the said fall block and the said cross-head members, a hook engaging the fall block to prevent tilting thereof, a pivotal connection between the said hook and the said cross-head members, and a releasing mechanism for said hook comprising a member slideable vertically to the standard and a linkage coupling said members to the hook which permits the cross-head members to cant and swivel on the swivel block without effecting the hook releasing gear.

50 2. The combination claimed in claim 1, wherein a lug is provided on the fall block having an aperture to receive a hook on a davit for supporting the boat from a davit when the boat is stowed therein.

55 3. In combination a boat and launching tackle therefor comprising a fall block having a sheave for a loop of a fall rope, openable means normally closing the block to maintain the fall rope loop within the block, and a permanent connection between the fall block and the boat.

60 4. In combination a boat and launching tackle therefor comprising a fall block having a sheave for the loop of a fall rope, openable means normally closing the block to maintain the fall rope within the block, and a swivelling permanent connection between the fall block and the boat to permit the fall block to swivel in the boat about a vertical axis.

65 5. In combination a boat and launching tackle therefor comprising a fall block having a sheave for the loop of a fall rope, openable means normally closing the block to maintain the fall rope within the block, and a cantable permanent connection between the fall block and the boat,

whereby the block can cant about a horizontal axis.

6. In combination a boat and launching tackle therefor comprising a fall block having a sheave for the loop of a fall rope, a standard permanently mounted in the boat, a hinged connection between the said standard and the said fall block whereby the block can be tilted to cast off the loop of a fall rope, and means for maintaining the fall rope in alignment with the fall block during launching of the boat.

7. In combination a boat and launching tackle therefor comprising a fall block having cheek plates, one of which is movable to open the block for casting off the loop of a fall rope and a sheave for the loop of the fall rope rotatably mounted between the cheek plates, means for maintaining the cheek plates closed around the sheave to keep the fall rope in alignment with the sheave during lowering of the boat and a permanent connection between the fall block and the boat whereby the fall block is retained in the boat after the fall rope has been cast off.

8. In combination a boat and launching tackle therefor comprising a fall block having cheek plates one of which is movable to open the block for casting off the loop of a fall rope, a sheave for the loop of the fall rope, located between the cheek plates and rotatably mounted on the movable cheek plate, means for maintaining the cheek plates closed to maintain the sheave in alignment with the fall rope during lowering of the boat and a permanent connection between the fall block and the boat whereby the block remains in the boat after the fall rope has been cast off.

9. In combination a boat and launching tackle therefor comprising a fall block having a sheave on to and off which the loop of the fall rope can

be slipped, a bracket permanently secured to the boat, a hinged connection between the fall block and the bracket to permit the fall block to tilt about a horizontal axis out of alignment with the fall rope to cast said fall rope off the sheave, a hook adapted to engage a part of the fall block to prevent tilting thereof and maintain the sheave in alignment with the fall rope and a hinged connection between said hook and the bracket.

10. In combination a boat and launching tackle therefor comprising two fall blocks, one at each end of the boat, each fall block having a sheave onto and off which the loop of a fall rope can be slipped, two brackets, one for each fall block permanently secured one at each end of the boat, a hinged connection between each fall block and its bracket to permit the fall block to tilt about a horizontal axis out of alignment with the fall rope, to cast the loop of the fall rope off the sheave, two hooks, one hinged to each bracket and adapted to engage a part of the fall block connected thereto to prevent tilting of said block and maintain the sheave of the fall block in alignment with the fall rope, a releasing mechanism and an operative connection between each hook and said releasing mechanism, said releasing mechanism having a common operating member for disengaging the hooks from the respective fall blocks when the fall ropes are to be cast off.

11. The combination claimed in claim 9 and further comprising two detent devices, one located in the path of travel of each hinged hook to prevent the disengagement of the hook from its block except when the detent is first released.

IVAN RUPERT FLEMING.
FRANK ELDER FLEMING.
